UNITED STATES PATENT OFFICE.

SIDNEY H. WHEELHOUSE, OF ST. LOUIS, MISSOURI, ASSIGNOR TO THE UNITED STATES HEAD-LIGHT COMPANY, OF UTICA, NEW YORK.

DESIGN FOR A HEADLIGHT-CASE FOR LOCOMOTIVES.

SPECIFICATION forming part of Design No. 30,334, dated March 14, 1899.

Application filed June 23, 1898. Serial No. 684,696. Term of patent 14 years.

To all whom it may concern:

Be it known that I, SIDNEY H. WHEELHOUSE, a citizen of the United States, residing at St. Louis, in the State of Missouri, have 5 invented and produced a new and original Design for a Headlight-Case, of which the following is a specification, reference being had to the accompanying drawings.

This invention relates to a new and original 10 design for a headlight-case for locomotives.

The leading feature of my design consists in the body of a headlight-case formed cylindrical in its general contour, with its rear end closed, its front end open, and provided with 15 a rim surrounding the said open end. The said cylindrical body is provided with inclined signal-number plates arranged on its sides, as shown in the drawings and as more fully hereinafter described.

20 In the said drawings, Figure 1 is a perspective view, and Fig. 2 a plan view, of the headlight-case.

1 represents the body of the case, and 2 the front rim, which surrounds the front or open

end thereof. Outwardly-projecting walls 4, 25 5, and 6 form a frame, one of which is located on each side of the cylindrical body 1. These frames incline outwardly from the front toward the rear of the case, and each of the frames contain a plate 7, adapted to bear sig- 30 nal characters.

The case is provided with a base 8 and a ventilating-dome 9, having a hood 10, and at one side of the case is a door 11, hinged at 12 to the back 13 and provided with a handle 14. 35

Having thus fully described my invention, I claim—

The design for a headlight-case for locomotives, substantially as herein shown and described.

In testimony whereof I have hereunto set my hand, in the presence of two witnesses, this 18th day of June, A. D. 1898.

SIDNEY H. WHEELHOUSE.

Witnesses:

F. T. HYNDMAN,
E. F. HYNDMAN.
